Primary Examiner — Kendra Leslie Hamilton(74) *Attorney, Agent, or Firm* — Nelson Mullins Riley & Scarborough, LLP(57) **CLAIM**

The ornamental design for an oral motor chew tool, substantially as shown and described.

DESCRIPTION

FIG. 1 is a top, front, left perspective view of an oral motor chew tool, showing our new design;

FIG. 2 is a bottom, front, left perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a rear elevation view thereof; and,

FIG. 8 is a front elevation view thereof.

The central portion shown in broken lines in FIGS. 2 and 4 forms no part of the claimed design.

1 Claim, 6 Drawing Sheets
